CONTINUITY CHECKER OR THE LIKE

Norman Frank Pickering, Pacoima, Calif., assignor to
Special Devices, Inc., Fernando, Calif., a corporation of
California

Filed Apr. 14, 1961, Ser. No. 64,744

Term of patent 14 years

(Cl. D26—5)

Fig. 1.

Fig. 2.

Fig. 3.

FIGURE 1 is a top plan view of a continuity checker or the like, showing my new design;

FIGURE 2 is a view in section along the line 2—2 of FIGURE 1;

FIGURE 3 is a view in section along the line 3—3 of FIGURE 1, and

FIGURE 4 is a perspective view of my continuity checker or the like showing the lid thereof in a closed position. The internal storage means in the lid have been omitted for clarity.

The dominant features of my new design are shown in solid lines in the drawing.

I claim:

The ornamental design for a continuity checker or the like, substantially as shown and described.
